UNITED STATES PATENT OFFICE.

WILLIAM J. WILLIAMS, OF FRANKLIN, PENNSYLVANIA.

PROCESS OF ROLLING TIE-PLATE BARS.

No. 921,043.

Specification of Letters Patent.

Patented May 11, 1909.

Application filed May 22, 1908. Serial No. 434,336.

To all whom it may concern:

Be it known that I, WILLIAM J. WILLIAMS, citizen of the United States, residing at Franklin, in the county of Venango and 5 State of Pennsylvania, have invented a certain new and useful Improved Process of Rolling Tie-Plate Bars, of which the following is a specification, reference being had therein to the accompanying drawing.

10 My invention relates to a process of rolling tie plate bars such as are disclosed in my pending application filed May 22, 1908, Ser. No. 434,335, which plate consists of a plate proper having upon its lower face one or 15 more longitudinal flanges or ribs and upon the upper face thereof a series of rail engaging studs which are in vertical alinement with and positioned directly over the flanges or ribs.

20 In the present drawing I have shown one way of carrying out my present process, by reference to which drawing it will be noticed that Figure 1, is a perspective view of finishing rolls showing a tie plate bar passing 25 through the same, one end of the bar being shown in the finished state and the other in the semi-finished state. Fig. 2, is an elevation of the rolls shown in Fig. 1. Fig. 3, is a cross section through the tongue 5 and depression 6 of the roll 2. Fig. 4, is a cross section of the semi-finished bar. Fig. 5, is a cross section of the finished bar.

The blank or semi-finished bar as shown at A in Fig. 1 and in section in Fig. 4, consists of a strip of metal having longitudinal ribs 7 on its upper surface, thereby forming an intervening groove 7^a therebetween. The lower face of the bar A also has flanges or ribs 3. The bar A may be rolled into its ribbed form 40 in any well known manner from a billet or other original shape.

45 After the bar has been formed with the ribs and flanges, I place it in the rolls which have a closed pass and are provided with means for displacing the metal of the ribs into the flanges, means being provided, however, so as to leave transverse alining lugs 8 at intervals apart, alternating with plane surfaces B, the lugs being left over or in 50 alinement with the flanges 3.

I effect the required rolling of the bar by the type of rollers shown in Figs. 1, 2 and 3 of the drawings, by reference to which it will be seen the lower roll 1 has grooves 3' to receive and finish the flanges 3 of the plate. 55 The roll 1 also has collar portions 4—4 on

each side of the grooved part, the collars being of larger diameter than the grooved part to leave a plate pass which is closed. The roll 2 has grooves to receive the collars 4—4 of the roll 1, as shown in Fig. 2.

The tongue 5 on the upper roll 2 has suitably spaced pockets 6 into which some of the metal of the ribs 7 is admitted as the bar is passed through the closed pass between the rolls 1 and 2, to leave an undepressed part of the ribs 7 in the form of lugs 8.

In practice the ribs 7 on the preformed bar have slight sloping sides and rounded corners, see Fig. 4, the ribs leaving grooves 7^a between one another in the plate, as shown in Fig. 4. In passing through the final finishing rolls the bar is changed in shape from that shown in Fig. 4 to the final shape shown in Fig. 5, by the displacement of the metal from the ribs 7 into the flanges 3 sufficiently to form the flanges 3 in the desired final shape.

The provision of the closed pass between the rolls, formed by the tongue 5 projecting between the collars 4—4, enables the rolling to be carried out without a depression of the edge of the plate at the location of the studs, and also prevents the formation of a line of projecting metal along the side of the bar, as would be the case were ordinary superimposed rollers used.

As the bar passes through the rolls the lower edges of the flanges 3 are properly formed and sharpened. The difference in 90 the shape of these flanges before and after passing through the rolls being respectively indicated in Figs. 4 and 5, of the drawings.

From the foregoing description, taken in connection with the accompanying drawings, it is thought the complete construction, operation and advantages of my invention will be readily understood by those skilled in the art to which this invention appertains.

What I claim is:

1. The process of manufacturing a tie plate blank which consists in first rolling a billet of metal into a continuous tie plate bar having longitudinal ribs on one surface and longitudinal flanges opposed thereto on the other surface, and then rolling the bar so as to displace a part of the metal of the ribs into the flanges. 10

2. The process of manufacturing a tie plate blank, which consists in rolling a billet of metal into a continuous tie plate bar having a plane under-surface provided with lon- 11

2

5 gitudinal flanges and a plane upper surface provided with longitudinal ribs, the ribs and flanges being located opposite each other and then passing said strip through rolls having a properly shaped closed pass to displace some of the metal of the ribs into the flanges and leaving projecting lugs formed by un-displaced portions of the ribs.

10 3. The process of manufacturing a tie plate bar which consists in first rolling a suitable body of metal into a bar having longitudinal ribs on one face thereof and oppositely positioned flanges on its other face and then rolling said body in such manner as 15 will displace a portion of the metal of the ribs into the flanges and so as to leave trans-verse shoulders or lugs alternating with plane surfaces on one surface of the bar.

15 4. The process of rolling tie plate bars which consists in utilizing a bar having upon one face thereof a plurality of longitudinal flanges and upon the opposite face thereof a corresponding number of ribs positioned op-

posite said flanges and in passing said bar through final finishing rolls having thereon a 25 closed pass adapted to the final finishing of said flanges and constructed to displace a part of the metal of the ribs into the flanges and leave lugs at intervals.

5. The process of rolling tie plate bars 30 which consists in first rolling a suitable body of metal into a bar having longitudinal ribs upon one face thereof and oppositely positioned flanges on its opposite face, then rolling a portion of the metal of the ribs into 35 the body of the plate and into the flanges to cause the final shaping of said flanges and leaving portions of the metal of the ribs in the form of lugs substantially as shown and described.

In testimony whereof I affix my signature in presence of two witnesses.

40 WILLIAM J. WILLIAMS.
